UNITED STATES PATENT OFFICE

RODOLPHE BERTHON, OF NEUILLY, FRANCE, ASSIGNOR, BY MESNE ASSIGNMENTS, TO
KISLYN CORPORATION, OF NEW YORK, N. Y., A CORPORATION OF DELAWARE

FILM FOR COLOR CINEMATOGRAPHY

Application filed June 26, 1928, Serial No. 288,499, and in France July 2, 1927.

The methods of cinematography in colours in which coloured nets or nets with microscopic refracting elements are used are, generally speaking, based on the inversion method such as practised for "autochrome" plates; one of them being based on the feature of obtaining negatives from which positives are printed, as is practised for black and white pictures.

10 The present invention relates to a modification of the emulsion used on films goffered with microscopic refracting elements, which modification has the effect of permitting negatives to be obtained that are suitable for printing positives, as desired, by projection.

This modification consists in incorporating into the sensitive emulsion a substance adapted to prevent any diffusion of light from reflection on the adjacent grains of bromide or 20 of any other silver salt employed, so that only such rays as have directly passed through the refracting elements of the backing can attack the silver salt while the reflected rays are deprived of all photographic activity. The substances to be used are generally black, brown 25 or yellow colouring agents, but I can also use certain emulsified salts such as silver chromate. Whatever the substances used, they must be liable to complete elimination by 30 means of suitable baths.

The panchromatic emulsions intended for obtaining negatives should utilize, preferably, dark colouring agents such as indulines; while the positive emulsions, the normal sensitivity of which is limited to blue radiations, may utilize a yellow colouring agent such as tetrazine. In both cases the colouring agent acts by subduing the reflected rays more energetically than the transmitted rays.

40 If insoluble salts are added to emulsions, such addition must be made to the emulsion itself previous to the latter being spread on the backing. If, on the contrary, colouring agents are used, they may, as desired, either 45 be mixed with the emulsion or used afterwards to dye the gelatine of the film by wetting. For the panchromatic film, the dyeing may be effected either before or after 50 panchromatization, if the latter is itself effected by wetting.

Films so obtained are specially applicable to methods or processes which involve the use of films having linear microscopic elements, such films being intended for printing by optical obliteration of the network on projection. They are applicable also to processes involving the use of films goffered with picots, specks or dots, as, for example, the so-called Keller-Dorian method. Lastly, they are not limited to cinematography but are 60 serviceable for all and any photographic processes in which lenticular nets are employed.

The invention will be more fully understood from the accompanying drawing, the 65 single figure of which is a sectional view of a fragment of film on a greatly enlarged scale.

In said drawing, A indicates the goffered face of the film; B the support or backing 70 of celluloid or other transparent material; and C the sensitized layer.

Taking, for consideration, a light ray or beam 1 which strikes the sensitized layer C, it will print this layer, but a part of the ray will be reflected, first according to line 2 and then again, at the goffered surface, according to line 3, and it will form an image at D' which is a duplicate of image D. Two further reflections then occur according to 80 lines 4 and 5, and there is danger of a third image D'' of the point D being formed.

It will be seen, therefore, that it is of great importance to render the reflected rays 2, 3, 4 and 5 non-actinic, in order to eliminate the 85 formation of images D' and D''.

I claim as my invention:

1. A color motion picture film having a flexible base supporting a single layer of emulsion on one side thereof and having the 90 other side provided with a multiplicity of refracting elements, said other side being so disposed as to receive the light striking the film and to transmit it to the emulsion, and said emulsion having incorporated therein 95 a substance which will tend to prevent the reflection of actinic rays transmitted to the emulsion through the base.

2. A color motion picture film having a flexible base supporting a single layer of 100

emulsion on one side thereof and having the other side provided with a multiplicity of refracting elements, said other side being so disposed as to receive the light striking the film and to transmit it to the emulsion; and said emulsion having incorporated therein a coloring agent which will tend to prevent the reflection of actinic rays transmitted to the emulsion through the base.

10 3. A color motion picture film having a flexible base supporting a single layer of emulsion on one side thereof and having the other side provided with a multiplicity of refracting elements, said other side being so 15 disposed as to receive the light striking the film and to transmit it to the emulsion, and said emulsion having incorporated therein an emulsified salt which will tend to prevent the reflection of actinic rays transmitted to 20 the emulsion through the base.

In testimony whereof I affix my signature.
RODOLPHE BERTHON.
